UNITED STATES PATENT OFFICE.

DANIEL W. WILLIAMS, OF NEW ORLEANS, LOUISIANA.

CONSTRUCTING CHANNELS THROUGH SAND BARS IN HARBORS.

SPECIFICATION forming part of Letters Patent No. 252,917, dated January 31, 1882.

Application filed October 18, 1881. (No model.)

To all whom it may concern:

Be it known that I, DANIEL W. WILLIAMS, of the city of New Orleans and State of Louisiana, have invented a new and Improved Method 5 of Constructing Channels through Sand Bars in Harbors, Rivers, Bays, &c.; and I do hereby declare that the following is a full and exact description thereof, reference being had to the accompanying drawings, forming part 10 thereof, in which—

Figure 1 is a perspective view of my device. Fig. 2 is a plan of a harbor provided therewith. Fig. 3 is a view of one form of the piles which I employ.

15 The nature of my invention consists of the insertion of piles or planks upon sand bars in harbors, rivers, bays, &c., along and across the place through which it is desired to construct a channel in such a manner that the action of 20 the water upon and around such piles or planks will wash away and remove the sand of which such bars are composed, and thus form a channel through the same.

To enable others to use my invention, I will 25 proceed to describe my method of constructing a channel through sand bars in harbors, &c.

I use a boat or scow, as shown in Fig. 1, having holes or apertures through the deck and hull thereof, through which a number of planks 30 or piles, A A A, are inserted vertically in such a manner that they may be raised and lowered by means of a windlass, B, or blocks and falls,

or other device, so that such planks or piles may rest upon and sink into sand bars C when placed thereon along and across the place upon 35 such bars through which it is desired to construct a channel in such a manner that the action of the water upon and around such planks or piles will remove and wash away the sand of which such bars are composed, and thus by 40 removing such sand form a channel through said bars. I also use such planks or piles without a boat or scow by sinking them into the sand on such bars along and across the place where it is desired to construct a channel, as 45 shown and designated by the letters A A A in Fig. 2, and also marked + to designate the position of the planks or piles when used without a boat or scow.

What I claim as my invention, and desire to 50 secure by Letters Patent, is—

A method of constructing channels through sand bars in harbors, rivers, bays, &c., by the insertion of planks or piles into such bars along and across the place through which it is de- 55 sired to construct a channel in such a manner that the action of the water upon and around such planks or piles will remove and wash away the sand of which such bars are composed, and thus form a channel through the same.

DANIEL W. WILLIAMS.
